SYSTEM FOR COUNTERACTING UNDESIRED OSCILLATIONS IN ALTERNATING CURRENT CIRCUITS

Application filed April 28, 1926. Serial No. 105,059.

The invention relates to a system for the prevention of undesired or stray oscillations or oscillations of regeneration in an alternating current circuit, and more particularly to the counteracting in electrical circuits, as radio frequency receiving and transmitting circuits, of objectionable oscillations set up therein. In tuned radio frequency receiving circuits, for example, such as the typical circuits embodying one or more stages of radio frequency amplification, it frequently occurs in the operation of the same that disturbing oscillations develop as a result of the production of a regenerated wave. These oscillations have a frequency slightly higher or lower than that of the wave the circuit has been tuned or adjusted to; and the resulting heterodyning of the waves of slightly different frequencies produces beats resulting usually in a musical note or in a hiss which interferes with the reception. Sharply tuning the grid and plate circuits, also, may result in a regenerated oscillation, due to magnetic and dielectric coupling of said circuits.

The system of the present invention contemplates counteracting such undesired oscillations by associating or electromagnetically coupling with a circuit one or more stabilizing circuits, each consisting of two circuit portions wherein are set up voltages counteracting induced voltages of regeneration developed in the part of said original oscillating circuit with which each respective circuit portion is coupled. Heretofore, it has been proposed to provide in the original circuit an exactly opposed impedance, or to provide therein a definite opposing electromotive force. Both of these expedients, if the adjustments are only slightly out, can be offset by raising or by lowering the total admittance of the tuned grid circuit and so permit of tuning at two different dial settings. The result is broad tuning and inability completely to eliminate incipient undesired oscillations unless a considerable excess of nega-

tive impedance and consequent low efficiency are allowed. The novel system on the contrary relies on no exact impedance effect with current variable, nor fixed impedance with its current controlled by some other part of the circuit, due to magnetic coupling or direct series connection, but utilizes an arbitrary fixed impedance and variable current, not controlled by magnetic coupling due to neutralization of the magnetic coupling nor by direct connection to some other part of the circuit, but by a voltage balance in a tapped coil system.

The nature of the invention, however, will best be understood when described in connection with the accompanying drawing which is a diagrammatic representation of a typical radio receiving circuit embodying, for example, two stages of radio frequency amplification and a detector, with the novel stabilizing circuit associated with grid inductances thereof.

Referring to the drawing, the invention is illustrated as applied to a tuned radio frequency circuit embodying by way of example two stages of radio frequency amplification; and to this end comprises generally the first transformer 10, amplifying tubes 11 and a detector tube 12, with intermediate amplifying transformers 13 and the tuning condensers 14. The particular circuit set forth is shown merely by way of example; and it is to be understood that the invention is not restricted to the particular character of circuit shown but is applicable to various circuits wherein disturbing oscillations may develop due to certain conditions or characteristics inherent in the circuit or from an outside source.

To overcome the effect of such undesired oscillations there is arranged to be associated with said circuit the herein-described stabilizing circuit, which may be applied in multiple when additional stages of amplification are present. This stabilizing circuit comprises

an inductance 20 and an inductance 21, across which latter is bridged a variable condenser 22—the inductance 20 being connected to said inductance 21 substantially at the mid-point of the same in order that the values of the inductance in the portion thus divided may be substantially equal. A condenser 23, preferably variable, is included in series with the inductance 20 and a junction point 25. Two closed circuit portions are thereby formed of the stabilizing circuit, the one comprising the inductance 21, condenser 22 and leads to connect the same to the junction point 25 thru which it is connected by a lead 26 to the radio frequency circuit. The other closed portion comprises the inductance 20, the condenser 23 and the two parallel paths thru inductance half 24, and inductance half 27 and condenser 22 to the junction point 25 as well as leads to effect the connections. I have found for a tuned radio frequency amplified circuit, having a range of from 200 to 500 meters with transformers of 6 to 60 turns on 3" diameter core, that the inductance 21 should consist of a coil of 2" diameter and of approximately 35 turns, while the inductance 20 might consist substantially of a coil of 3" diameter and of 4 turns, with capacities of the condensers 22 and 23 varying approximately from 0 to .0005 mfd.

The aforesaid inductances 20 and 21, which may be variable if desired, are to be coupled in electro-magnetic relationship with any inductances of the radio frequency circuit between which a tendency toward regeneration exists, for example in this case, the inductance 20 may be coupled and preferably in close relationship with the secondary of the first transformer 10 while the inductance 21 is to be coupled but more loosely with the secondary of the first of the amplifying transformers 13. The stabilizing circuit as a whole is connected thru the junction point 25 and lead 26 to the receiving circuit at a point of predetermined potential; or the junction point may be directly grounded. It is to be understood that the relationship of the inductances 20 and 21 respectively to the secondary of the first transformer 10 and secondary of transformer 13 is such that the magnetic effects due to induced voltages of regeneration set up in one of a coupled pair are counteracted by the opposing effects introduced into the other pair, which in turn transmits the counteraction to the original oscillating circuit.

As set forth, the stabilizing circuit consists of two portions each adapted to counterbalance an induced voltage such as may be caused by regeneration in their respective coupled circuits. Instantaneous current flowing from inductance 20 to the junction point 25 divides equally at tap 28, due to the equal impedances of the paths having leading and lagging reactances to currents,

said paths comprising top point 28, inductance 27, condenser 22 and junction point 25, and tap point 28, inductance 24 and the junction point 25 respectively; as adjusted by condenser 22 and indicated by proper balance or by the resultant tone. The inductances 24 and 27, as stated, are equal and therefore the magnetic effects of the equal currents are equal and opposite or neutralized. This neutralizes the magnetic coupling between the two circuit portions. The currents prevailing in each portion are variable and independent, due to neutralization of magnetic coupling between them; and each current assumes its proper value as may be shown by the following considerations of the actions involved. An induced voltage of regeneration predominating in inductance 20 will increase the current in the corresponding circuit portion and therefore the voltage across the impedance of inductance 24. The increased voltage due to potential balancing in the other circuit portion will send back a voltage counteracting the initial induced voltage. This new current will alter slightly the neutralized magnetic coupling and may be adjusted by condenser 22 so that impedance of inductance 24 will be equal to the resultant impedance of inductance portion 27 and capacity of condenser 23. Similarly, an induced voltage predominating in inductance 21 will increase the current in its corresponding circuit portion. The decrease of currents follow by like reasoning. The approximate proportion of currents is obtained by means of condenser 23 which thereafter may remain practically fixed. Thus, both currents reach their proper value for any particular condition of circuit balance. The current prevailing in either inductance 20 or 21 automatically adjusts itself to counterbalance the induced regenerated current in the circuit coupled therewith, without relation to the other current or any other part of the general circuit. This results in a highly efficient circuit, perfectly balanced.

While the embodiment of the invention is herein shown as applied specifically to a radio frequency circuit, it is to be understood that the same is equally applicable to the counteracting of undesired or stray oscillations of regeneration in audio frequency circuits.

I claim:

1. In a system for counteracting undesired oscillations in a radio frequency circuit of two stages of tuned radio frequency amplification: a stabilizing circuit including two closed circuit portions each containing an inductance electromagnetically coupled respectively to two of the grid circuits of the radio frequency circuit and also thru a junction point; variable condensers included in both of the circuit portions; and leads connecting the two portions to each other in manner

such that the inductance of the one is connected substantially at the midpoint of the inductance of the other.

2. In a system for counteracting undesired oscillations in a radio frequency circuit including a tuning portion: a stabilizing circuit coupled thereto through a junction point and through two coupling inductances, one inductance being connected to the other substantially at its mid-point to form therewith a closed circuit portion and the divided inductance being coupled loosely to the said tuning portion, and a condenser in said closed circuit portion; and a condenser in a closed circuit portion including the divided inductance and the junction point.

In testimony whereof I affix my signature.
